UNITED STATES PATENT OFFICE.

WILLIAM D. MARKS, OF WESTPORT, NEW YORK.

DRIVING AND TRANSMITTING MECHANISM FOR WHEELED VEHICLES.

No. 918,685.

Specification of Letters Patent.

Patented April 20, 1909.

Application filed May 26, 1905. Serial No. 262,505.

To all whom it may concern:

Be it known that I, WILLIAM D. MARKS, a citizen of the United States, and a resident of Westport, Essex county, New York, have invented certain Improvements in Driving and Transmitting Mechanism for Wheeled Vehicles, of which the following is a specification.

My invention relates to mechanism for transmitting power to drive wheeled vehicles, and consists of certain improvements in transmitting, reversing and speed changing mechanism applied to an improved type of self-propelled car or locomotive in which an internal combustion engine may be employed as the source of power.

In the particular embodiment of my invention I make use of a pair of engines between which is located the power transmitting shaft, the reversing gear and the mechanism for changing or reducing the velocity of the speed transmitted. The power transmitting or driving shaft is connected by means of extension couplings and universal joints to line-shafts carrying wheels or disks having heavy pins, and these, in turn, mesh with and serve to drive similar wheels or disks carried by the car axles, the whole forming a flexible and massive linkage.

My invention further consists of a special form of clutch for locking the driving and reverse gear to the motor shaft; a special form of speed changing gear with which a similar form of clutch is employed, and other details of construction which will be more fully pointed out hereinafter.

A further feature of my invention consists in mounting the motors; the speed transmitting and speed changing mechanism and the reversing gear in a cradle supported by the truck bolsters of the car and disposed substantially in the center of the latter, entirely independent of the car body, the power being transmitted to said axles by the pin gears through the medium of extension couplings, universal joints and swiveling hangers as noted above; making a flexible transmission adapting itself to the swiveling of the car trucks and the movements of the car axles.

My invention is fully shown in the accompanying drawings, in which:

Figure 1, is a side elevation of a car to which the improvements forming the subject of my invention have been applied, showing the mechanism disposed entirely be-

neath the car; Fig. 2, is a diagrammatic plan view of the trucks, the motor supporting structure and the driving mechanism, the car being shown in dotted lines; Fig. 3, is a plan view of the speed transmitting and reversing mechanism; Fig. 4, is a sectional view of the speed changing mechanism, taken on the line *a—a*, Fig. 3; Fig. 5, is an enlarged sectional view of the reversing mechanism, taken on the line *b—b*, Fig. 3; Fig. 6, is a sectional elevation of the pin gearing for transmitting movement from the linkage shafts to the car axles, showing also the swiveling hanger; Fig. 7, is a plan view of a portion of this pin gearing; Fig. 8, is a reverse plan view of a part of Fig. 6; Figs. 9 and 10, are sectional views illustrating the universal joint employed in connection with the transmitting mechanism forming the subject of my invention; Figs. 11 and 12, are sectional views illustrating the extension joint employed in connection with the transmitting mechanism forming the subject of my invention; Figs. 13, 14, 15, 16, 17 and 18, are views illustrating details of the clutch forming the subject of my invention; Figs. 19 and 20, are views of the speed changing gear, and Fig. 21, is a sectional perspective view of one of the pins.

One of the most important features of my invention is the driving of all four axles of the car with an equal velocity ratio; the entire weight of the car riding upon such axles being employed for adhesion and tractive effort.

The cradle 1, carried beneath the center of the car 2 and formed of suitable I-beams or other metal shapes, supports the motors or other driving means and the speed changing and reversing mechanism. The ends 3 of this cradle are connected to a false body bolster of the car, and the support for the driving mechanism can thereby be made wholly independent of the car body.

A central longitudinal shaft 4, forming the power transmitting shaft, is connected, by means of universal joints 5 and extension couplings 6, with line-shafts 7 and 8, disposed beneath the trucks 9, each of which shafts carry two pin gear disks 10, which in turn mesh with pin gear disks 11 carried by the axles 12 of said trucks. This pin gearing forms a very important part of my invention and of the power transmitting mechanism forming the subject of the same. Each of

the shafts 7 and 8 are mounted in swiveling journals or bearings 15 supported by the axles 12 of the trucks, and such journals or bearings are so arranged as to permit rocking movement of these joints. The pin gearing forming the subject of my invention is a decided departure from the ordinary type of gearing employed for transmitting motion in driving vehicles of heavy type. The disks 10 forming part of this gearing are quite large, being about eighteen inches in diameter, and each carrying pins 16, in the present instance six in number set equi-distantly and as near as practicable to the margin or rim of such disks. These pins in turn mesh with similar pins carried by the disks 11 of the truck axles. The pins which I employ are composite in their structure, being made up of a core or stem 19, driven by hydraulic pressure into apertures 20 formed in the disk; such core being centrally bored at 21 from end to end. The apertures in the disks to receive the cores are enlarged at 22 just below the surface of the disk, and carried by the cores are the sleeves 23, which extend into these enlarged portions of the sockets, and, while being free to turn therein, provide an oil-tight cover for such core, so that the inner surface of the same may be lubricated by an internal oil supply. The inner end of these sleeves is provided with lugs 24 to receive the head 25 of a bolt 26, which bolt extends through the central bore of the core and is fastened by means of a nut 30 or cotter pin 27. A leather washer 28 is interposed between the sleeve and the bottom of the recess receiving the same. These pins and their rotatable sleeves which may be made of any desirable material, are quite massive, being nearly four inches in diameter, which is equal, in the present instance, to the distance between the centers of the shafts carrying the same, and for the greatest efficiency they should bear this relation to the shafts. Being of such size, they are practically indestructible and will be unaffected by dirt, grit, wood or stones raised from the roadbed of the track; in most cases throwing such material aside or grinding it between their engaging surfaces, at the same time the sleeves are free to turn and the wear of the same is quite inappreciable.

The linkage shafts 7 and 8 are supported by saddles 30 carried by the axles 12, such saddles having sleeves 31 surrounding said linkage shafts, and forming the bearings 15. The saddles are supported by side lugs 32 of collars 33 carried by the rear axles. These collars are loose on the axles, and being in engagement with the linkage shafts compensate for the movements of the latter due to undulations or irregularities in the roadbed. The linkage shafts are connected by means of universal joints 5 and extension couplings 6 with the driven or power transmitting shaft

4, which carries a loose disk 35 having pins 36 of the same general character as those carried by the disks 10 and 11, which disk 35 is driven from the bottom by means of the disks 37 and 38 carried by the driving shaft 39. Only one of these disks forms a transmitting element at one time, the other rotating idly on the shaft. To throw either of the disks 37 or 38 into engagement with the shaft 4, I provide a special form of clutch for each disk, and means for throwing said clutches. This comprises a sleeve 40 splined to said shaft 39 and carrying clutch engaging members 41 at each end, such sleeve being actuated by suitable means to cause it to move either clutch into engagement with one of said disks. With especial reference to Fig. 5, showing a sectional elevation of the reversing mechanism, and Figs. 13 to 18, inclusive, illustrating the details of the same, I will explain the construction and operation of the clutches employed in connection with this part of my invention. These clutches are of a new type which I have termed "bandage friction" clutches, and as they are duplicated a description of one will be sufficient. Independent eccentrically or concentrically mounted arms 42 are carried by the disks 37 and 38; which, when turned on their bearings 43 by the engagement of the moving sleeve 40, grip the engaging portion 44 of the latter. Combined with such eccentric members is a band spring 45 coiled a number of times and passed through openings in the bearings 43 of said members. By this means a very strong gripping effect distributed equally on each member can be secured upon the sleeve, which is splined to and turns with the shaft 39, and absolute rigidity of the parts connected secured. These clutches are employed in connection with the disks 37 and 38, each of which is provided with pins forming the driving means, and serve to transmit the movement of the motors to the driving shaft 39. Normally, these disks are free to rotate on said shaft 39, but as a matter of fact, one of them is generally clutched to such shaft. Formed on the inner sides of the disks are a series of ribs 46 having recesses 47 to receive the coiled band spring 45 having a number of laps or layers; in the present instance sixteen in all. This "spring bandage", as I have termed it, is confined by a series of collars 48 adapted to the recesses 47 in said ribs and held in place by cover plates 49 fastened at one end by a screw 50, and confined at the opposite end by the sleeves of the pins connected to the disks. There are usually six of the ribs 46, and the spring or bandage is supported at six equi-distant points. Under normal conditions the disks are free to rotate on the shaft 39 as may be readily noted. For the purpose of clutching them to said shaft, however, the following means are provided, it being understood that

but one clutch is operated at a time, and that both clutches are constructed exactly alike. Disposed alternately with respect to the ribs are a series of eccentric or concentric members 43, each having an opening 51, which may be off-set as noted in Fig. 16, or centrally disposed as shown in Fig. 18, which serves to receive the coils of the band spring. Surrounding these eccentricities are straps 52 having arms 42 with concaved engaging faces or brake shoes 53 whose curvature is on the arc of a circle struck from the center of the disk, and these bearing faces are preferably formed on renewable blocks 54. The series of spring coils being secured in their cross sectional area, the eccentric or concentric members 43 will be firmly confined thereto and there will be no danger of their displacement. To keep the bands or straps with their engaging faces turned outward for engagement with the expanding member, I employ springs 55 secured to side extensions 56 of the members 43 and bearing against pins 57 and 58 on the straps 52, such springs serving to turn the strap and throw the engaging face outward when the expanding member carried by the sleeve has been retracted, while the opposite end of such spring prevents such movement of the band as would displace its engaging portion. The "spring bandage" as I have termed it, equalizes the pressure upon each brake shoe. The clutch on the other disk is identically the same.

Carried by the shaft 39 is the sleeve 40, splined to said shaft, and to which means are attached for shifting it from one clutch to the other so as to take power from both engines. This sleeve carries at each end the cup-shaped clutch engaging members 41 recessed at 59 to fit over the hubs 60 of the disks, and having external flanges 61 to engage the arms 42 of the straps encircling the members 43. As such sleeve is longitudinally moved on the shaft 39, the engagement of these parts shifts the straps 52 on their eccentric or concentric members 43 and tends to expand the coiled spring, changing its form from that approximating a true circle as shown in Fig. 13, to a hexagonal contour as shown in Fig. 14, the projecting arms gripping the surface 44 of the cup-shaped ends 41 of the sleeve. The end pressure of such projections due to the change of form of the coiled spring is enormous, and the contact being close to the center of rotation there is no possible chance for slipping, and a positive clutch of enormous power is obtained.

The sleeve 40 is splined to the shaft 39 by means of four feathers 62, as clearly shown in Fig. 5, and this connection will insure sufficient engagement between these parts. To insure the ready movement of the sleeve on the shaft 39, I provide the shaft with a number of oil holes 63 and 64 in order to flood the

space between these members and each of the several bearings; the latter being provided with packing 65 of dope to which oil is passed through centrally bored holes 66 in the shaft 39 communicating with the holes 63 and 64. It will be noted that I provide special means of securing a plentiful supply of oil to the journals of the disks and other bearings of the main driving shaft.

The motors are connected to the flange couplings 67 at the ends of the shaft 39. When the shifter sleeve 40 is in the position shown in the drawings, the motors are driving the car forward, and to reverse the direction of movement of the car it is only necessary to shift the sleeve on the shaft 39, when the present driving disk will be disengaged and the clutch of the other one will be thrown in, and the car will be driven backward. This movement of the sleeve 40 is accomplished by means of a worm 70 carried by a rod 71, which is operated by hand wheels 72 on each platform of the car. The worm engages a toothed segment 73 of a lever 74 carried by a stud or spindle 75, the opposite end of which has a yoke arm 76 connected to a collar 77 mounted on the shifter sleeve 40, and by this means the said sleeve may be shifted on said shaft 39 and cause either of the disks 37 or 38 to be thrown into positive engagement with said shaft.

The shaft 4 forms a part of the linkage train, and in addition to the loose disk 35, it carries means for throwing into gear the speed changing mechanism. A pair of clutches or brakes are employed in connection with this mechanism which are of similar type to those just described, and the clutching members act against the beveled faces 78 and 79 of a suitable drum 80, which is loosely mounted on a sleeve 88 carried by the shaft 4. This drum has a series of arms 82 set at equi-distant points, which carry nuts 83 engaged by threaded portions 84 of a series of rods 85, said rods having pinions 86, which are turned in unison by a gear wheel 87 mounted on the shaft 4 and thrown into engagement to shift the drum uniformly when it is desired to change the speed.

The shaft 4 carries a pair of cannons 88 and 89, each of which is keyed to a disk 90 and 91, carrying clutches 92 and 93. To the shaft 4 a "sun" pinion 94 of an epicyclic train is keyed or otherwise secured, the "planet" pinions of which, three in number and indicated at 95, are carried by shafts or spindles 96 journaled in said disk 35. Each of these pinions 94 and 95 are provided with the same number of teeth, in the present instance twenty-two. Each of the cannons 88 and 89, carry "sun" pinions 97 and 98, the pinion 97 having twenty-five teeth, while the pinion 98 has twenty-three teeth. Meshing with the pinion 97 are three "planet" pinions 99 carried by the shafts or

spindles 96 and having nineteen teeth each. These pinions form part of an epicyclic train for reducing the speed of the disks 37 and 38 and transmitting about one-fourth 5 of the same to the shaft 4. Meshing with the pinion 98 are three "planet" pinions 100, also carried by the shafts or spindles 96 and having twenty-one teeth. These pinions form part of an epicyclic train for reducing 10 the speed of the disks 37 and 38 and transmitting one-eleventh of the same to the shaft 4. All intermediate speeds are obtainable by advancing the time of the spark to effect 15 explosion and drive the engine at varying speeds. When the disk of the cannon 88 is clutched to said drum, the speed transmitted will be about one-fourth of that generated by the engines; when, however, the drum is shifted so as to be clutched with the disk 20 on the cannon 89, the speed transmitted will be about one-eleventh of that generated by the engines.

It will be noticed that the form of clutch employed in connection with the speed change 25 is substantially the same as that employed in connection with the means for reversing the direction of rotation of the power transmitting shaft. The difference, however, lies in the fact that whereas in the reversing mechanism 30 the pressure members turn on eccentric or concentric hubs, in the speed change such pressure members 42^a are moved outwardly by the beveled faces of the sliding drum. In both instances, however, the coiled spring 35 "bandages" are employed.

It will be noticed that the pins carried by the disks on the linkage shafts 7 and 8, the truck axles 12, and the loose disk 35, are provided with beveled ends, while the pins 40 on the disks 37 and 38 are not beveled. In gearing of this character when the driving and driven shafts are mounted in the manner I have shown and described, the engagement 45 of a pin on a disk of the lower shaft when the latter is the driving element and when turned in the direction of the arrow *x*, Fig. 6, is directly against the body of the pin. When turned in the opposite direction, however, with the lower shaft as the driving element, 50 the surface of the pins of the lower disk engages the marginal end of the other pins and unless such pins are beveled to permit the passage of the other pins, the gearing will jam. It is therefore necessary to bevel both 55 sets of pins carried by the disks of the shafts 7 and 8 and the axles of the trucks, and the disk 35, but it is not necessary to bevel the pins of the disks 37 and 38; as the pins of both of these disks at their point of engagement are below the pins of the disk 35 and therefore never engage the ends of the same.

The linkage shafts for transmitting the movement to the various car axles are connected with the power shaft from the engine 60 by means of universal joints 5 at their ends,

which are clearly shown in Figs. 9 and 10, and by extension joints 6, a detail of which is shown in Figs. 11 and 12, and these extension joints in turn have other universal joints at their opposite ends. The extension 70 joints are in part of ordinary construction, comprising a squared shank 101 fitting a squared recess 102 in a squared shell 103. To the opposite ends of these members the yokes 104 for the universal joints are 75 secured, which yokes are held in place by flat keys 105 driven into recesses formed half in the yoke and half in the shank of the extension joint members. In addition to the squared portion of these members, a guiding 80 stem 107 is carried by the internal member and slides in and out of a circular opening in the other member, preventing jamming or gouging by the squared portion. The universal joints are substantially the same as 85 those in common use, and their yokes 108 are held to the shafts by means of keys 109 driven into recesses in the manner shown, and as described with reference to the extension couplings. The pivot pins 110 of the 90 yokes are seated or journaled in a block 111, and the novel feature of this invention consists in making such blocks hollow and closing its open ends with plates 112 making 95 fluid-tight joints. The chamber 113 thus provided is kept full of oil to afford constant lubrication for the pivot pins of the yokes connected to said block, such chamber being filled through the opening 114, closed by a 100 screw plug 115.

In the structure shown and described herewith, the pitch diameter of the pin disks are equal, in consequence of which the diameter of said pins is equal to the distance between the centers of the shafts carrying the same, 105 and their ends are beveled as described to facilitate their engagement when driven in certain directions. When the pitch diameters of the pin disks are not equal, however, the pins may have epicycloidal and hypocycloidal axial sections. 110

In pin gearing of the character forming the subject of my invention, the pins being of such massive size, means must be provided for reducing the noise ordinarily occasioned by their engagement. The sleeves carried by the pins are arranged to rotate with respect thereto and this will in a measure dissipate the objectionable noise. To remove it entirely, however, I provide the surface of 115 the sleeves with a special composition that is, both non-wearing and non-resonant. 120

The sleeve prepared in accordance with this part of my invention is fully shown in the perspective view, Fig. 21. The sleeve 23 is 125 provided with shoulders 120 at each end, forming a recess on the surface between said shoulders, and in this recess is wound a strip, or strips 121 of raw-hide, saturated with water, the ends being secured by suitable 130

means. The sleeve thus prepared is soaked in pitch at 212° F., which action drives out the moisture and replaces such moisture with pitch. The sleeve is then coated with a composition consisting of equal parts of bitumen and hydraulic cement and after this has set, it may be turned and trued to the desired shape. Other means of providing a non-resonant surface for the sleeves are possible, such for instance, as filling the space or recess of the same with aluminum-babbitt metal or other non-resonant anti-friction metal. The recess within the sleeve is filled with fibrous material 122 retained by a wire gauze plate 123, and this fibrous material is filled with oil to lubricate the surfaces of the pin and sleeve.

Having thus described my invention, I claim and desire to secure by Letters Patent:—

1. In driving mechanism for self-propelled cars, the combination of a truck having the usual wheels, axles for said wheels suitably journaled therein, heavy disks keyed to said axles, a driven shaft disposed at right angles to and supported by said axles, said driven shaft crossing said axles, heavy disks carried by said shaft, and pins carried by said several disks for mutual engagement whereby the axles may be actuated by said driven shaft, said disks being of the same diameter and the pins of the same meshing at a point offset with respect to their axial lines.

2. In driving mechanism for self-propelled cars, the combination of a truck having the usual wheels, axles for said wheels suitably journaled therein, disks keyed to said axles, a shaft supported by said axles and crossing the same, said shaft being disposed at a right angle with respect to the axles, disks carried by said shaft, pins carried by said disks for mutual engagement whereby the axles may be actuated by the movement of said shaft, a driving shaft, and means for transmitting the movement of said driving shaft to the shaft supported by the axles, said disks being of the same diameter and the pins of the same engaging at a point offset with respect to the axial lines of said disks.

3. In driving mechanism for self-propelled cars, the combination of a truck having the usual wheels, axles for said wheels suitably journaled therein, disks carried by said axles, shafts supported by said axles and crossing the same, said shafts being disposed at right angles to the axles, disks carried by said shafts, pins carried by said several disks for mutual engagement whereby the axles may be actuated by said shafts, a driving shaft, a series of universal extension joints serving to connect and transmit the movement of said driving shaft to the shafts supported by the several axles, said disks being of the same diameter and having their pins meshing at a

point offset with respect to the axial lines of said disks.

4. In driving mechanism for self-propelled cars, the combination of a truck having the usual wheels, axles for said wheels suitably journaled therein, disks carried by said axles, shafts supported by said axles and crossing the same, said shafts being disposed at right angles to the axles, disks carried by said shafts, pins carried by said several disks for mutual engagement whereby the axles may be actuated by said shafts, a motor, a shaft driven thereby, a series of universal extension joints serving to connect the driving and driven elements and transmitting the movement of said motor driven shaft to the shafts supported by the axles, said disks being of the same diameter and having pins which engage at a point offset with respect to the axial line of said disks.

5. In driving mechanism for self-propelled cars, the combination of the driving shaft, a driven shaft or axle, the driving shaft being disposed at right angles to and crossing the driven shaft, a second driven shaft or axle disposed in the same relative position, gearing carried by said shafts whereby they may be driven, bearing blocks whereby the driving shaft is supported by the driven shafts, and swiveling saddle blocks combined therewith to take up the rocking motion due to undulations caused by irregularities in the roadbed.

6. In driving mechanism for self-propelled cars, the combination of the driving shaft, a driven shaft or axle, the driving shaft being disposed at right angles to and crossing the driven shaft, a second driven shaft or axle disposed in the same relative position, gearing carried by said shafts whereby they may be driven, bearing blocks whereby the driving shaft is supported by the driven shafts, and means combined therewith to take up the rocking motion due to undulations caused by irregularities in the roadbed.

7. In driving mechanism for self-propelled cars, the combination of a driving shaft, a driven shaft or axle, the driving shaft being disposed at right angles to and crossing the driven shaft, a second driven shaft or axle disposed in the same relative position, gearing carried by said shafts whereby they may be driven, and swiveling supports carried by the driven shafts and supporting the driving shaft.

8. In driving mechanism for self-propelled cars, the combination of a driving shaft, two sets of driven shafts or axles, the driving shaft being disposed at right angles to and crossing the driven shafts, gearing carried by said shafts whereby the parts may be driven, swiveling supports carried by the driven shafts and supporting the driving shaft, and a motor disposed between said sets of driven shafts for actuating the driving shaft.

- 6
9. In a self-propelled car, the combination of a truck, axles carried thereby, wheels on said axles, pin disks carried by said axles, shafts supported by said axles, pin disks carried thereby for engagement with the pin disks of the axles, a motor, a shaft driven thereby, and a series of extension and universal joints for transmitting the movement of the same to the shafts supported by the axles.
10. The combination, in a self-propelled car, of a pair of motors, a shaft disposed between the same and driven in one direction only, power transmitting members carried by said shaft and adapted for transmitting the movement of such shaft in opposite directions, and means for connecting said members to the shaft.
11. The combination, in a self-propelled car, of a pair of motors, a shaft disposed between the same and driven in one direction only, power transmitting members carried by said shaft and adapted for transmitting the movement of such shaft in opposite directions, clutches carried by said members, and means for shifting said clutches.
12. The combination, in a self-propelled car, of a pair of motors, a shaft disposed between the same and driven in one direction only, power transmitting members loose on said shaft and adapted for transmitting the movement of such shaft in opposite directions, clutches carried by said members, a movable sleeve splined to the shaft for shifting said clutches, and means for moving said sleeve.
13. In a self-propelled car, the combination of a truck, axles carried thereby, a driving shaft, the latter being disposed at right angles to the axles and as close as convenient to the same, disks carried by the axles, disks carried by the driving shaft, and pins carried by said disks for engagement with each other whereby said axles may be driven from said shaft, said disks being of the same diameter and the diameter of said pins being equal to the distance between the centers of the axles and said driven shaft.
14. In a self-propelled car, the combination of a truck, axles carried thereby, a driving shaft, the latter being disposed at right angles to the axles and as close as convenient to the same, disks carried by the axles,
- disks carried by the driving shaft, and pins carried by said disks for engagement with each other whereby said axles may be driven from the shaft, said disks being of the same diameter and the diameter of said pins being equal to the distance between the centers of the axles and said driven shaft, said pins having beveled ends to facilitate their engagement when driven in certain directions.
15. In a self-propelled car, the combination of the trucks, axles carried thereby, driving shafts disposed at right angles to said axles, disks carried by the driving shafts, disks carried by the axles, pins carried by said disks for engagement with each other whereby the axles may be driven by said shafts, said disks being of the same diameter and the diameter of said pins being equal to the distance between the centers of the shafts and said axles, said pins having beveled ends to facilitate their engagement for being driven in certain directions, and rotatable sleeves carried by said pins.
16. In a self-propelled car, the combination of the trucks, axles carried thereby, a driving shaft disposed at right angles to said axles, disks carried by the axles, disks carried by the driving shaft, pins carried by said disks for engagement with each other whereby the axles may be driven by said shafts, the diameter of said pins being equal to the distance between the centers of the shafts, said pins having beveled ends to facilitate their engagement for being driven in certain directions, rotatable sleeves carried by said pins, and a covering of non-resonant material for said sleeves.
17. In a self-propelled car, the combination of a truck, axles carried thereby, a driving shaft disposed at right angles to and crossing said axles, disks on said axles and shaft, pins on said disks for engagement whereby the axles may be driven by the shaft, rotatable sleeves carried by said pins, means for holding said pins in place, and means for lubricating said sleeves.
- In testimony whereof, I have signed my name to this specification, in the presence of two subscribing witnesses.

WM. D. MARKS.

MURRAY C. BOYER,
Jos. H. KLEIN.
